UNITED STATES PATENT OFFICE.

HOWARD EARL HOOVER, OF CHICAGO, ILLINOIS, ASSIGNOR TO THE HOOVER SUCTION SWEEPER COMPANY, OF NEW BERLIN, OHIO, A CORPORATION OF OHIO.

BRUSH-SUPPORT FOR SUCTION-CLEANERS.

1,324,195.

Specification of Letters Patent.

Patented Dec. 9, 1919.

Application filed September 29, 1917. Serial No. 194,068.

To all whom it may concern:

Be it known that I, HOWARD EARL HOOVER, a citizen of the United States, residing at Chicago, in the county of Cook and State 5 of Illinois, have invented a certain new and useful Improvement in Brush-Supports for Suction-Cleaners, of which the following is a specification.

My invention relates to improvements in 10 brush supports for suction cleaners and has for one object to provide a new and improved form of support whereby the brush of a suction cleaner may be removably and adjustably mounted in the open suction 15 mouth. Another object is to provide means whereby the brush will be held during operation in such manner that inadvertent and accidental changes in adjustment will be impossible. Another object is to provide 20 means whereby the brush may be easily and conveniently adjusted when the operator desires to make an adjustment. Another object is to provide means whereby the brush shaft is securely held in position 25 during the operative period but can be easily removed when desired to permit the removal of the brush and its associated parts. Another object of my invention is to provide means whereby the brush can be 30 adjusted without removing the brush shaft. Further objects of my invention will appear from time to time in the specification.

It will be understood that the power 35 driven brush of my type of suction cleaner gradually wears away, that is, the ends of the bristles break and grind off and from time to time the brush must be moved down toward the floor so that the bristles may be able to continue in contact with the floor 40 and accomplish their purpose. My invention relates, therefore, among other things to means whereby the brush may be held in proper position in the open suction mouth and whereby it may be adjusted toward and 45 from the floor.

My invention is illustrated more or less diagrammatically in the accompanying drawings wherein:—

Figure 1 is a section through a part of 50 my suction cleaner showing the suction nozzle, brush and driving parts;

Fig. 2 is a section through one end of the suction hood with brush removed;

Fig. 3 is a section along the line 3—3 of 55 Fig. 2 with the brush in position;

Fig. 4 is a similar section on the line 4—4 of Fig. 2 looking in the direction of the arrows with the parts in the position shown in dotted lines in Fig. 2 and the shaft partly removed;

60

Fig. 5 is a detailed cross section;

Fig. 6 is a detail of a thread guard.

Like parts are indicated by like characters in all the figures.

A is a motor housing. It contains a motor armature A¹ driving a fan A² in the fan chamber A³ which communicates with an open mouth suction hood A⁴, the open mouth of which is parallel with and adapted to be above the surface upon which the 65 housing travels by means of wheels A⁵ A⁶. A⁷ is a pulley on the fan.

B is a beating and sweeping brush rotatably mounted in the open mouth hood on the shaft B¹ and it carries a pulley B² over 70 which travels a belt B³ driven by the pulley A⁷. B⁴ are bearings in the ends of the hollow brush body engaging the shaft and projecting slightly beyond the ends of the brush body. B⁵ are thread guards flanged 75 to overhang the ends of the brush at B⁶ and provided with hubs B⁷ engaging the outwardly projecting ends of the bearing B⁴. Thus there is a clearance between the thread guards and the end of the brush all the 80 way around. These thread guards are apertured at B⁸ in register with apertures B⁹ in the adjusting plates B¹⁰, B¹¹.

The shaft B¹ extends at either end slightly beyond the two thread guards. One end is 85 cut away as indicated at C to engage a substantially semicircular hole C¹ in the adjusting plate B¹⁰. The other end of the shaft engages a circular hole C² in the adjusting plate B¹¹ and is in register with a 90 hole C¹² in one of the swinging plates C³. This arrangement holds the shaft against 95 rotation when the parts are in operative position but makes it possible to withdraw it through the holes C² and C¹² when the 100 parts are removed from the suction mouth so as to disengage the brush and thread guards. These shaft ends terminate short 105 of the interior surface of the housing. Each one of the plates B¹⁰, B¹¹ is pivotally mounted on one of the swinging plates C³ which swinging plates are pivoted on the end wall of the suction hood. The pivot point of the swinging plate and the pivot point of each adjusting plate is on the side of the 110

suction mouth toward the fan. The belt between the fan and fan pulley and brush pulley is rubber and under tension and tends to exert a pressure yieldingly rotating each 5 of the swinging plates C^3 into the closed position thus holding the brush in the hood and making it difficult to withdraw it until the belt is taken off the fan pulley. C^5 , C^5 are indicating lines carried by the adjusting plates C^3 , C^3 opposite the points C^{15} on the swinging plates C^3 so as to indicate the 10 position of the two adjusting plates B^{10} , B^{11} and enable the person who is making the adjustment to set them in the same relative 15 position.

To limit the movement of each adjusting plate on its swinging plate and to enable the operator to set it in any given position within the limits, I provide a screw C^4 which 20 is attached to and projects inwardly from each swinging plate and which extends through a slot C^{16} in the adjusting plate. This defines the limit of excursion or rotation of the adjusting plate on the swinging 25 plate. I also provide a thumb nut C^{17} on the outer end of the screw and by it the adjusting plate can be locked in any desired position with reference to the swinging plate. Thus by moving one adjusting plate to say 30 the third indicating line and then locking it in position by the thumb nut an accurate position of the parts can be accomplished by in like manner moving the other adjusting plate to the third line and then locking 35 it in position. The limit of excursion of the adjusting plate is preferably such that the brush can never be lowered so far that the belt will come into contact with the floor covering when it is drawn up against the 40 suction mouth. I preferably place beneath the thumb nut a lock washer C^{18} . It will be observed that the line of tension exerted by the belt usually passes adjacent the pivot of the adjusting plate so that the lever arm 45 through which a force is exerted tending to rotate the adjusting plate out of position is a short one and thus a slight resistance to movement is sufficient to hold the adjusting plate in position on the swinging plate. The 50 two swinging plates C^3 are apertured as at C^{12} in register with the ends of the shaft and also in register with apertures B^9 in the adjusting plates and apertures C^9 in the housing whereby an air current is permitted 55 to be drawn in from the outside through the swinging plate, the adjusting plate, the threadguard and across the end of the brush into the casing. These apertures are arranged arcuately as indicated and so positioned that no matter what the position of the adjusting plates these apertures will always be open and they will always permit a free flow of air inwardly through the apertures and about the end of the brush. C^9 is 60 a spacing bar extending across between the 65

swinging plate C^3 located adjacent the forward boundary of the open mouth of the suction hood and adapted to space the parts in position and insure accurate alinement of the brush shaft supporting mechanism. 70

On the bottom of the plate C^3 are lateral flanges C^{19} which underlie the edge of the casing and serve as a stop to prevent the swinging and adjusting plates from moving too far into the casing and to also serve as a 75 means of attachment for the converter which is on occasions applied to the inlet mouth of the suction cleaner.

On the threadguard B^5 is a projecting pin B^{25} adapted to be fitted into the notch B^{26} on the adjusting plate. This device is to prevent any tendency of the threadguard to rotate. The end of the shaft which projects into close proximity with the inner wall of the end of the casing is preferably beveled 85 so as to make it easy to insert the shaft in the openings in the adjusting and swinging plates.

It will be evident that while I have shown in my drawings an operative device, still 90 many changes might be made both in size, shape and arrangement of parts without departing materially from the spirit of my invention and I wish, therefore, that my drawings be regarded as in a sense diagrammatic. 95

The use and operation of my invention are as follows:—

Starting with the parts in the full line position if the motor is driven the brush will be rotated. As the suction cleaner is used the power driven brush will gradually wear away, the brush bristle ends will become short and finally a condition will be reached where the brush bristles are so short that they do not effectively operate upon the 105 floor covering. It becomes necessary to lower the axis of rotation of the brush so as to bring the bristles into contact again. This is done by first throwing the belt off the brush pulley. This releases the tension 110 which normally holds the brush frame in the open mouth of the hood and the operator may then by seizing the bar extending across between the swinging plates rotate the assembly out of the mouth of the nozzle. He 115 may then rotate the adjusting plate downwardly on the swinging plate preferably one line. Then the parts should be locked together by operating the thumb nut. The same operation should then take place at 120 the other end of the brush, care being taken to move the two adjusting plates the same distance as for example in the case for illustration of one line. If desired, of course, the movement could be extended over two or 125 more lines. In any event this adjustment will bring the brush nearer to the floor. The parts are then swung back into position and the machine is ready for use with the brush adjusted to a lower position. The 130

swinging plates are held in operative position by their engagement with the inside surfaces of the ends of the casing. The adjusting plates are held against the swinging plates by the thumb nuts. Under these circumstances the parts cannot be sprung apart so as to permit the shifting of the adjusting plates. The belt when placed in position tends to hold all the parts in operative relation. As previously suggested the swinging plates, adjusting plates and brush are prevented from passing too far into the casing by the engagement of the flanges C¹⁹, C¹⁹ with the edge of the casing.

15 If for any reason as for example to put in a new belt it is desirable to disassemble or take down the parts this may be done when they are swung out in the position shown in Fig. 4 by removing the shaft 20 which can be drawn outward in one direction only and when reinserted is held in position against rotation by the engagement of its non-circular inner end with the aperture in the adjustment plate. The shaft will be 25 held in this position from longitudinal movement when the parts are in operative position within the casing by the engagement of the end of the shaft with the wall in the end of the casing.

30 It will be noticed that the guard fingers as illustrated for example in Fig. 1 are placed substantially parallel with the floor or floor covering and in the plane of the lower part of the inlet mouth. This serves as an 35 index to determine the degree of adjustment required for the brush.

We have used the word "removed" as applied to the brush carrying frame. By this we shall of course be understood as including such a meaning as would permit the frame to be bodily removed or to be partially removed by being swung out of the mouth in position for manipulation.

I claim:

45 1. In a suction cleaner the combination of a hood with a brush supporting frame removably mounted therein, a brush shaft mounted on the frame, a brush with a hollow body rotatably mounted on the shaft 50 the frame apertured to permit the endwise removal of the shaft to release the brush from the frame.

55 2. In a suction cleaner the combination of a hood with a brush supporting frame removably mounted therein, a brush shaft mounted on the frame, a brush with a hollow body rotatably mounted on the shaft the frame apertured to permit the endwise removal of the shaft to release the brush 60 from the frame, the parts proportioned so that the shaft is held from longitudinal motion when the frame is within the hood.

65 3. In a suction cleaner the combination of

a hood with a brush supporting frame removably mounted therein, a brush shaft 65 mounted on the frame, a brush with a hollow body rotatably mounted on the shaft the frame apertured to permit the endwise removal of the shaft to release the brush from the frame and means for locking the 70 shaft from rotation on the frame.

4. In a suction cleaner the combination of a hood with a brush supporting frame removably mounted therein, a brush shaft 75 mounted on the frame, a brush with a hollow body rotatably mounted on the shaft the frame apertured to permit the endwise removal of the shaft to release the brush from the frame and means for locking the shaft from rotation on the frame comprising a 80 non-circular opening in the frame and a co-acting portion of the shaft adapted to be received therein.

5. In a suction cleaner the combination of a hood with a brush supporting frame removably mounted therein, a brush shaft 85 mounted on the frame, a brush with a hollow body rotatably mounted on the shaft the frame apertured to permit the endwise removal of the shaft to release the brush from the frame and thread guard devices 90 loosely mounted on the shaft between the ends of the brush body and the supporting frame.

6. In a suction cleaner the combination of a hood with a brush supporting frame removably mounted therein, a brush shaft 95 mounted on the frame, a brush with a hollow body rotatably mounted on the shaft the frame apertured to permit the endwise 100 removal of the shaft to release the brush from the frame and thread guard devices loosely mounted on the shaft between the ends of the brush body and the supporting frame, and means for locking the thread 105 guards against rotation.

7. In a suction cleaner the combination of a hood with a brush carrying frame removably mounted in the hood and containing end parts and brush carrying parts adjustably mounted on the end parts and a brush 110 mounted on the brush carrying parts.

8. In a suction cleaner the combination of a hood with a brush carrying frame pivotally mounted in the hood and containing end parts and brush carrying parts adjustably mounted on the end parts and a brush 115 mounted on the brush carrying parts.

In testimony whereof, I affix my signature in the presence of two witnesses this 12th 120. day of September 1917.

HOWARD EARL HOOVER.
